Primary Examiner — Ian Simmons*Assistant Examiner* — Richelle G Shelton(74) *Attorney, Agent, or Firm* — Dorsey & Whitney LLP**CLAIM**

We claim the ornamental design for a base for water flosser, substantially as shown and described.

DESCRIPTION

FIG. 1 is a front, left isometric view of a base for water flosser.

FIG. 2 is a rear isometric view of the base of FIG. 1.

FIG. 3 is a front elevation view of the base of FIG. 1.

FIG. 4 is a rear elevation view of the base of FIG. 1.

FIG. 5 is a right side elevation view of the base of FIG. 1.

FIG. 6 is a left side elevation view of the base of FIG. 1.

FIG. 7 is a top plan view of the base of FIG. 1; and,

FIG. 8 is a bottom plan view of the base of FIG. 1.

The broken line showing of a reservoir and areas immediately adjacent to the shaded areas represents boundaries to the claimed design with the broken line itself and all lines within forming no part of the claimed design.
